COMBINED ASH TRAY AND CIGARETTE HOLDER

Eric Wedemeyer, Floral Park, N. Y., assignor to Hamilton Art Metal Corporation, New York, N. Y., a corporation of New York

Application May 20, 1954, Serial No. 30,571

Term of patent 14 years

(Cl. D85—2)

Fig. 1.

Fig. 2.

Fig. 3.

Fig. 1 is a side view of a combined ash tray and cigarette holder, showing my new design, the other side being like the side shown;

Fig. 2 is a top plan view thereof; and
Fig. 3 is a perspective view thereof.

I claim:

The ornamental design for a combined ash tray and cigarette holder, substantially as shown and described.
